[57] CLAIM

The ornamental device for a floor structure for amusement devices or the like, substantially as shown and described.

DESCRIPTION

FIG. 1 is a top plan view of a floor structure for amusement devices or the like;
FIG. 2 is a side view in elevation of one of the sides of the view of FIG. 1, the other three sides being identical to that of FIG. 2;
The bottom is plain and unornamented.

Fig. 1.

Fig. 2.
